UNITED STATES PATENT OFFICE.

JAMES J. COLES, OF LOS ANGELES, CALIFORNIA.

CAP AND COLLAR CASE.

Application filed October 22, 1923. Serial No. 670,175.

To all whom it may concern:

Be it known that I, JAMES J. COLES, a citizen of the United States, residing at Los Angeles, in the county of Los Angeles and 5 State of California, have invented certain new and useful Improvements in Cap and Collar Cases, of which the following is a specification.

The present invention relates to a cap 10 and collar case and has for its principal object to provide a case wherein both a cap and a plurality of collars may be carried conveniently, said case being adapted to be placed within a carrier such as a suit 15 case or the like.

A prime object of the invention is to provide a case of this nature embodying a simple and efficient construction, one which is inexpensive to manufacture, durable, attractive in appearance, and well adapted for 20 the purpose designed.

With the above and numerous other objects in view which will appear as the description progresses, the invention resides 25 in certain novel features of construction and in the combination and arrangement of parts as will be hereinafter more fully described and claimed.

In the drawings:

30 Figure 1 is a perspective view of the device embodying my invention showing the same in an open position;

Figure 2 is a vertical central longitudinal section therethrough showing the same 35 in a closed position; and

Figure 3 is a transverse section through the collar container.

Referring to the drawing in detail it will be seen that the device consists generally 40 of an outer case 1 and an inner case 2. The outer case 1 is the cap case while the inner case 2 is the collar case. The cap or outer case 1 includes a body portion 3 of substantial cylindrical formation or any other 45 desired shape and is provided with a short extension 4 having a flange 5 arranged thereabout, said flange being formed integral with the side wall of the body 1 as is also the extension 4. A tab 6 is disposed on the flange 5 and a cover 7 is hinged to the body 1 by means of a strap 8 so as to be brought over the body 3 and the tip compartment formed by the short extension 4 and flange 5 and to be held in place by the tab 6 engaging a button 9.

The collar case 2 will be formed of sub-

stantially the same material as the outer or top case and of substantially the same formation as the body 3 thereof, but of course will be smaller in size so as to be disposed 60 within the body 3. As is disclosed to advantage in Figure 2 the cap 11 is disposed in the outer case the crown thereof being positioned within the body 1 and the tip within the tip compartment formed by the 65 extension 4 and flange 5 and the collar case 2 is then inserted in the crown of the cap and the cover 7 may be closed over both cases. A pair of diametrically opposed tabs 12 are provided on the upper edge of 70 the case 2 so that it may be easily removed from the outer case when desired.

It is thought that the construction, advantages and other features of the invention will now be clearly understood without a 75 more detailed description thereof. It is desired, however, to point out the numerous changes in the details of construction and in the combination and arrangement of parts as will be hereinafter claimed may 80 be made without departing from the spirit or scope of the invention.

What is claimed is:

1. In a casing for caps, collars, etc., an outer container, an extension formed on the 85 forward edge of the container, the said container being adapted to receive a cap and the extension the peak thereof, an inner container loosely positioned in the outer container so as to be mounted within the interior of the cap, and a cover member hingedly mounted on the outer container adapted to enclose the same.

2. In combination, an outer container, a 90 comparatively wide extension formed near the upper edge of the container, a flange formed about the sides of the extension forming a continuation of the upper edge of the container, the said outer container and extension being adapted to receive a cap 95 therein, an inner container of cylindrical formation adapted to be positioned within the cap mounted in the outer container, ears formed on the upper edges of the inner container, and a cover member hingedly connected to the said outer container.

3. In combination, an outer container, a 100 comparatively wide extension formed near the upper edge of the said outer container, a flange formed about the edge of the said extension and forming a continuation of the 105 upper edge of the container, the said outer

container and extension being adapted to receive therein a cap and tip, an inner container substantially smaller than the outer container adapted to be readily positioned in the outer container and a cap is positioned therein, said inner container being adapted to contain collars and the like, ears formed on the upper edge of the inner container, and a hinged cover adapted to snugly fit upon the upper continuous periphery of the outer casing and extension for closing the same.

4. A casing for caps, collars etc., including a substantially oval shaped container, a comparatively wide extension near the upper edge of the said container, a flange formed about the edge of the said extension continuous with the upper edge of the container, and a cover member hingedly connected to the container adapted to snugly fit upon the continuous periphery of the container and extension flange.

In testimony whereof I affix my signature.
JAMES J. COLES.
